J. B. FREYSINGER

CYLINDER LOCK

Filed Feb. 6, 1923

Inventor

J. B. Freysinger

By Seymour & Bright

Attorneys

Patented Aug. 4, 1925.

UNITED STATES PATENT OFFICE.

JOHN B. FREYSINGER, OF STAMFORD, CONNECTICUT, ASSIGNOR TO THE YALE & TOWNE MANUFACTURING COMPANY, OF STAMFORD, CONNECTICUT.

CYLINDER LOCK.

Application filed February 6, 1923. Serial No. 617,362.

To all whom it may concern:

Be it known that I, JOHN B. FREYSINGER,
a citizen of the United States, and a resident
of Stamford, in the county of Fairfield and
5 State of Connecticut, have invented certain
new and useful Improvements in Cylinder
Locks; and I do hereby declare the follow-
ing to be a full, clear, and exact descrip-
tion of the invention, such as will enable
10 others skilled in the art to which it apper-
tains to make and use the same.

This invention relates to improvements in cylinder locks and more particularly to such as are provided with armor means,—one object of the invention being to provide a simple and efficient armored lock structure wherein the cylinder of the lock shall be protected from end to end and also at its forward end, against penetration of a boring tool, and to so construct the armor means that the same shall be secured to and held in close contact with the cylinder of the lock by means effecting a clamping of the armor to said cylinder and without the employment of fastening means entering the wall of the cylinder.

With this and other objects in view, the invention consists in certain novel features as hereinafter set forth and pointed out in the claims.

In the accompanying drawings,—

Figure 1 is a sectional view of a lock structure embodying my improvements.

Figure 2 is a front end view.

35 Figure 3 is a sectional view illustrating a modified form, and

Figure 4 is a front end view of the latter.

In the embodiment of the invention shown in Figure 1, a lock cylinder is represented at 1 and the plug or barrel at 2. A hardened metal armor shell (preferably hardened steel) surrounds the cylinder 1 from one end to end as shown at 3 and closely contacts with the exterior face of said cylinder. A hardened metal armor plate 4 is disposed in front of the cylinder 1 and an armor plate or disk 5 is revolvably mounted in an opening 6 in the plate 4 so as to be disposed in front of the plug 2 of the lock and this plate or disk 5 is provided with a key slot 7 to align with the key slot of the plug.

The plate or disk 5 is held in place by the plate 4 and the latter is secured in position by the annular, inwardly projecting flange or portion 8 at the front end of the armor shell 3. This annular flange may be formed by crimping or spinning the front end of the armor shell over the peripheral portion of the plate 4 and said shell is rigidly secured to the cylinder by crimping or spinning its rear end portion over the rear end portion of the cylinder, thus forming an inwardly projecting flange or part 9 at the rear end of the shell to engage the rear end of the cylinder. 55 60

In the embodiment of the invention shown in Figure 3, the armor shell 3 and the armor plate 4^a which is disposed in front of the cylinder are made integral with each other, and the rear end of the shell is crimped or spun to form an inwardly projecting flange 10 engaging the rear end of the cylinder. 65 70

In both forms of the invention, the rear end portion of the armor shell may be left unhardened in order to facilitate its crimping or spinning to form the inwardly projecting flanges which engage the rear ends of the cylinders. In the construction shown in Figure 1, the flange 8 at the forward end of the shell would preferably be formed before hardening and afterwards hardened. 75 80

Having fully described my invention what I claim as new and desire to secure by Letters-Patent, is:

1. The combination with a lock cylinder, of hardened metal armor means surrounding said cylinder and including a part in front of the cylinder, and means clamping the armor means to the cylinder at both ends thereof. 85

2. The combination with a cylinder lock of hardened armor for said lock, said armor comprising a hardened shell surrounding the cylinder lock from end to end thereof, and a hardened member in front of said lock and rigid relatively to said hardened shell, said hardened shell being provided at its rear end with an inward projection engaging the rear end of the lock.

3. The combination with a lock cylinder, of hardened steel armor therefor, said armor comprising a hardened steel shell surrounding the cylinder from end to end and having

an inwardly projecting annular end portion engaging the rear end of the cylinder, said armor also including a hardened metal member in front of the cylinder, the front end 5 of the armor shell having an inwardly projecting annular part engaging the rim portion of the hardened metal armor member.

In testimony whereof I have signed this specification in the presence of two subscribing witnesses.

JOHN B. FREYSINGER.

Witnesses:

CHARLES LEDIN,
CHARLES A. BERRY.
